HAIR WAVING MACHINE

Charles A. Fetter, Washington, D. C.

Application July 6, 1934, Serial No. 734,049

12 Claims. (CL. 132—36)

The invention relates to hair waving machines of the type used in hair dressing establishments, and wherein a waver reel casing is supported on a standard, and has for its object to provide means whereby the device will give the general appearance of a lamp above and adjacent a seat, and carried by a standard, thereby adding to the artistic appearance of the device and hiding the unsightly reel casing and curlers carried thereby.

5 Also to mount the reel casing so that it can be moved to a position above the seat for use.

A further object is to provide shade supporting means on the reel casing for supporting a shade housing the casing and a connection between the reel standard and the reel casing whereby the axis of the reel casing can be moved from the axis of the standard to a position above the seat to one side of the standard.

A further object is to form the standard and seat from tubing material.

A further object is to provide the upper end of the standard, which is in axial relation to the reel casing, with an upwardly offset horizontal arm extending across the axis of the standard and the reel casing and on which the reel casing is slidably mounted, thereby allowing the reel casing and the shade carried thereby to be radially moved in a horizontal plane to a position to one side of the standard and above the seat.

30 A further object is to form the seat and the standard from a single piece of tubing bent to form and as a unit thereby accurately placing the seat in relation to the head of a person in the seat and the reel casing when moved outwardly to a position above the seat.

A further object is to provide the upper end of the standard with an upwardly inclined arm slidably connected to the under side of the reel casing above the seat when the reel casing is in axial position in relation to the standard, said slidable connection forming means whereby the reel casing can be laterally moved and supported in a position above the seat and with the standard to one side of the reel casing.

45 A further object is to provide the under side of the reel casing with a guide extending diametrically across the same, and in which guide is slidably mounted the upper end of an angular portion of the standard within the shade, said angular portion, when the reel casing is extended assuming a position adjacent one side of the shade.

A further object is to provide an arcuate shaped horizontally disposed curtain rod supported by

the reel casing and movable therewith and adapted to assume a position in advance of the seat.

A further object is to provide the ends of the arcuate curtain rod with upwardly and inwardly extending arms supported by the upper side of the reel casing, and under which arms an operator may easily walk around the chair when the reel casing is in forward position above the chair.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of the seat, showing the reel support carried thereby and the shade and curtain rod in vertical longitudinal cross section.

Figure 2 is a bottom plan view of the reel casing, showing the guide carried thereby.

Figure 3 is an end view of the guide and the upper end of the standard.

Figure 4 is a top plan view of the device.

Figure 5 is a vertical transverse sectional view through the curtain rod.

Referring to the drawings, the numeral 1 designates the seat in which the customer is seated during a hair curling operation. The seat 1 is preferably formed from tubular material 2, and extending upwardly at the rear of the back 3 of the seat is a vertically disposed standard 4. In devices of this character as at present constructed, the reel casing 5, with the many dangling curlers 6, presents an unsightly arrangement, and one which detracts from the appearance of a shop.

The upper end of the standard 4 is in axial relation to the reel casing 5, as clearly shown in Figure 1, however to use the reel casing and reels carried thereby and curlers it is necessary to move the casing 5 from its full line position shown in Figure 1 to its dotted line position shown in said figure above the seat 1, and at which time the curlers 6 can be pulled downwardly from the reel casing and attached to the hair in the usual manner. It is to be understood however that the reel casing and curlers may be of any structure and applicant does not limit himself in this particular.

Supported on the upper side of the reel casing 5 by means of a channelled ring 8 is a downwardly flared shade 9 of the lamp type, and which shade is sufficiently large to conceal the curlers 6 from

view and to give the general appearance of a reading lamp adjacent the seat 1, thereby allowing the normally unsightly hair curling machine to present a more artistic appearance.

- 5 The upper end of the standard 4 which is axially disposed in relation to the reel casing 5 terminates in an upwardly and forwardly inclined arm 10 having a horizontal portion 11 in the diametrically extending guide 12 carried by the 10 under side of the reel casing 5 as clearly shown in Figure 2. It will be noted that the operator 15 can shift the reel and its shade from its axial position in relation to the standard 4 to the dotted line position above the seat 1 as shown in Figure 1, and after which movement the various curlers 6 may be lowered in the usual manner 20 for attachment to the hair. When the shade 9 and the reel is moved to a position above the chair, the arm 10 will assume a position adjacent the rear side of the shade 9, thereby still maintaining the general appearance of a lamp.

It is often desirable to place a curtain around the occupant of the seat and to accomplish this result the horizontally disposed arcuate curtain 25 rod 13 is provided forwardly of the reel casing 5 and of the lamp shade 9. It will be noted that the ends of the curtain rod 13 terminate in upwardly extending arms 14 which extend to a position above the reel casing 5, and are supported by the reel casing 5 through the medium 30 of the transversely disposed arms 15, under which it will be noted that an operator may walk behind the curtain 16 supported on the rod 13. When the rod and the reel on which it is mounted 35 is in forward position, it will be seen that the rod is forwardly of the seat 1, hence the operator may walk around the seat behind the curtain 6 while working on the customer.

From the above it will be seen that a combined 40 seat and curling machine is provided which will give the general appearance of a floor lamp adjacent the seat, and that the reel casing and the curlers carried thereby will be concealed from view when the reel casing is in operative or inoperative position.

The curtain 16 is supported on eyes 18 carried 45 by ball bearings 17 within the curtain rod as clearly shown in Figure 5, all of which is conventional structure.

50 The invention having been set forth what is claimed as new and useful is:

1. The combination with a hair waving machine said machine comprising an upwardly extending standard, a reel casing carried by the 55 upper end of said standard, a seat to one side of said standard, said reel casing being normally when in inoperative position in axial position on the standard and means connecting said standard and reel casing whereby said reel casing may be 60 moved from its axial position in relation to the standard to a position above the seat.

2. The combination with a hair waving machine comprising an upwardly extending standard, a seat to one side of said standard and in 65 fixed relation thereto, a waver reel casing con-

nected to the upper end of the standard in axial relation thereto and means whereby said waver reel casing may be moved to one side of the axis of the standard and to a position above the seat.

3. In combination, a hair waving machine, a seat to one side of said machine and in which a person is to be seated, a waver reel casing carried by the machine above the seat and normally to one side thereof and means connecting said reel casing and machine whereby said waver reel casing may be moved laterally to a position above the seat.

4. A hair waving machine comprising a seat, an upwardly extending reel casing standard to the rear of the seat, a reel casing connected to the upper end of said standard in axial relation thereto and means whereby said reel casing can be moved laterally from its axial position in relation to the standard to a position to one side of the standard above the seat.

5. A device as set forth in claim 4 including a shade housing the reel casing and movable therewith.

6. A device as set forth in claim 4 including a shade housing the reel casing and means carried by the shade and cooperating with the casing for maintaining said shade in position.

7. A device as set forth in claim 4 including a horizontal arm carried by the machine and slidably connected to the reel casing.

8. A hair curling machine comprising a seat, a reel casing, an upwardly extending standard to the rear of said seat, a horizontally disposed arm carried by the upper end of the standard and on which the reel casing is slidably mounted and 110 in axial relation to the standard, said reel casing being laterally movable on the arm to a position above the seat.

9. A hair curling machine comprising a seat, a vertically disposed standard to one side of the 115 seat, the upper end of said standard terminating in an upwardly inclined arm overlying the seat, a reel casing above the standard axial thereto and a slidable connection between the upwardly inclined arm and the reel casing.

10. The combination of a hair curling machine standard adjacent a seat, a reel casing above said standard in axial relation thereto, a downwardly extending shade carried by said casing and movable therewith, an upwardly inclined arm carried 125 by the standard within the shade and above the seat, said arm being slidably connected to the reel casing, said reel casing being diametrically movable in a lateral plane on the reel standard arm to a position above the seat.

11. A device as set forth in claim 10 wherein there is a dove-tail sliding connection between the reel casing and the upwardly inclined arm.

12. A device as set forth in claim 10 wherein the downwardly extending shade is downwardly 135 flared and the upwardly inclined arm assumes a position adjacent the inclined rear side of the shade when the reel casing is positioned over the seat.

CHARLES A. FETTERS. 140
